UNITED STATES PATENT OFFICE.

GEORGE H. CHANCE, OF PORTLAND, OREGON.

PICTURE-HANGER.

SPECIFICATION forming part of Letters Patent No. 701,149, dated May 27, 1902.

Application filed April 23, 1901. Serial No. 57,076. (No model.)

To all whom it may concern:

Be it known that I, GEORGE H. CHANCE, a citizen of the United States, and a resident of Portland, in the county of Multnomah and State of Oregon, have made a certain new and useful Invention in Picture-Hangers; and I declare the following to be a full, clear, and exact description of the same, such as will enable others skilled in the art to which it applies to make and use the invention, reference being had to the accompanying drawings, and to letters of reference marked thereon, which form a part of this specification.

Figure 1 is a side elevation of my device as applied to place the picture-hook in position. Fig. 2 is a front elevation of my device, showing the picture in part. Fig. 3 is a detail perspective view of the hanger-head.

The invention relates to devices for facilitating the operation of hanging pictures; and it consists in the novel construction and combinations of parts, all as hereinafter set forth.

In the accompanying drawings the letter *a* designates the end of a pole or rod of sufficient length to reach to the position of the picture-nail or hanger-molding on the wall. To this pole is attached the double-hook device *b*, having the shank *c* and the separated bent or angular arms *d d*, proceeding from the shank, these arms being overhanging, parallel, and terminating in the upturned hook ends *e e*, between which is an interval *f* of sufficient breadth to span the head of a picture-nail or the molding-hook *f'*. To the shank *c* on the opposite side from the hooks is connected a clasp or grip *g*, consisting of the rigid jaw *G* and the pivoted jaw *G'*, held normally pressed toward the fixed jaw by means of a spring *g'*. The pivoted jaw consists of a normally horizontal lever portion *g''*, to which the pull-cord *h* is attached, and a gripping portion *g''*, having a right-angular relation to such lever por-

tion. The pivot of the part *g''* is designated by reference-letter *Z*.

In order to hang a picture, the picture-cord *e'* is placed in position to engage the two hook ends *e e*, and when the instrument is raised the picture will be lifted by means of its cord. Between the hook ends the cord is exposed, so that the double hook can be placed with its arms or branches spanning the picture-nail or hook, over which the exposed portion of the cord between the hook ends is held. Then by lowering the instrument the cord will be left in proper position and in engagement with the picture-nail or molding-hook.

The instrument is serviceable not only for hanging the hooks and pictures, but also for taking them down or altering their position when desirable.

Having described this invention, what I claim, and desire to secure by Letters Patent, is—

A picture-hanging instrument having a vertical shank, a pair of jaws attached thereto, and extending horizontally therefrom, one of said jaws being rigidly attached to the shank, and the other of said jaws consisting of a horizontal bar pivotally attached near one end to the first jaw, and a gripping portion attached to the horizontal portion at or near the middle, means for attaching a pull-cord at the opposite end of said horizontal bar, and a spring for holding the pivoted jaw pressed toward the stationary jaw, substantially as specified.

In testimony whereof I affix my signature in presence of two witnesses.

GEORGE H. CHANCE.

Witnesses:

F. C. MILLER,
F. N. HENION.
